UNITED STATES PATENT OFFICE.

LEO ROSENMAN, OF NEWARK, NEW JERSEY.

FASTENER STRIP OR FLY FOR GARMENTS.

1,373,452.

Specification of Letters Patent.

Patented Apr. 5, 1921.

Application filed June 30, 1917. Serial No. 178,018.

To all whom it may concern:

Be it known that I, LEO ROSENMAN, a citizen of the United States, residing at Newark, in the county of Essex and State of New Jersey, have invented certain new and useful Improvements in Fastener Strips or Flies for Garments; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in a novel means and method of securing garment-fasteners, such as snap-catches comprising two members, one with a post and the other with a post-receiving socket, to garments or to the "flies" of garments; and, the present invention has reference, more particularly, to a foldably disposed strip of material, forming either a part of a garment or a separate strip adapted to be secured to the garment, said strip being provided with a special arrangement of stitching providing at intervals suitable pockets in which are loosely disposed the members of the snap-catches, and then providing the strip with another line of stitching for closing said pockets to thereto secure said catch-members within and against displacement from said pockets.

The present invention, therefore, has for its principal object to provide a simple and novel means and method of attachment of the respective members of garment-fasteners, such as snap-catches, to a garment, or to a strip or strips of material adapted to be secured to a garment, with a view of providing the strip with such snap-catches, the members of which are secured in place by suitable stitching, which stitching, however, does not pass directly through any parts of the fastener-members, but is located adjacent thereto, hugging the fastener-member in a manner to prevent lateral, rearward or forward motion of the fastener, as well as any tilting of the fastener when arranged in the said pockets.

Other objects of the present invention not at this time more particularly enumerated will be clearly understood from the following detailed description of the present invention. With the various objects of the present invention in view, the said invention

consists, primarily, in the novel "fly" and means of producing the same with pockets or receiving portions for the reception of the respective fastener members of snap-catches, adapted to retain the fastener-members in place against movement within and against accidental displacement of the fastener-members from said pockets or receiving portions, and without stitching or sewing directly through the fastener-members; and, the invention consists, furthermore, in the novel arrangements and combinations of the several devices and parts, as well as in the details of the construction of the same, all of which will be more fully described in the following specification, and then finally embodied in the clauses of the claims which are appended to and which form an essential part of the said specification.

The invention is clearly illustrated in the accompanying drawings, in which:—

Figure 1 is a face or plan view, showing fragmentary portions of two "flies" or strips, one for the usual post-members and the other for the usual socketed post-receiving members of snap-catches, provided with stitching forming pockets or receiving-ports for the respective fastener-members, showing one embodiment of the principles of the present invention; Fig. 2 is a transverse sectional representation of the same, said section being taken on line 2—2 in said Fig. 1, looking in the direction of the arrow α ; and Fig. 3 is a section of the said flies, taken on line 3—3 in said Fig. 1, the positions of the respective "flies" in said Fig. 3 being reversed.

Fig. 4 is a face view of the strip provided with the pockets or receiving portions for the reception of the socketed post-receiving members of the snap-catches, showing the reversed side or face of the strip from the same strip as represented in said Fig. 1; and Fig. 5 is a view of a portion of the said strip, showing its initial step of folding the strip and sewing or providing the same with stitching to provide pockets for the reception of the socketed post-receiving members of the snap-catches.

Fig. 6 is a face view of a portion of a pocketed strip for the reception of the post-members of the snap-catches, illustrating a slightly different arrangement of stitching for providing the strip with pockets; and Fig. 7 is a transverse section of the same, said section being taken on line 7—7 in said

Fig. 6, looking in the direction of the arrow *y*.

Fig. 8 is a face view of a portion of a pocketed strip for the reception of the post-members of snap-catches, said view illustrating still another arrangement of stitching for providing the strip with pockets; and Fig. 9 is a transverse section of the same, said section being taken on line 9—9 10 in said Fig. 8, looking in the direction of the arrow *z*.

Figs. 10, 11 and 12 are face views of fragmentary portions of strips, each strip being provided with a different arrangement of 15 stitching for providing the strips with pockets; Fig. 13 is a rear face view of the strip represented in said Fig. 12; and Fig. 14 is a transverse section, said section being taken on line 14—14 in said Fig. 12, looking in the 20 direction of the arrow *u*. Fig. 15 is a face view of another modification.

Similar characters of reference are employed in the said above described views, to indicate correspondings parts.

25 Referring now to the several figures of the drawings, the reference-characters 1 and 2 indicate respectively, the covering-strip and base-strip of a garment, both of said strips being of any suitable material, each 30 strip forming an integral part of the garment, or being made separate therefrom and sewed fast to the garment in any usual manner.

For the purposes of the present invention, 35 the covering-strip 1 will hereinafter be termed the socketed member receiving pocket-strip, and the base-strip 2 will hereinafter be termed the post-member receiving pocket-strip.

40 Referring now more particularly to Fig. 5 of the drawings, in producing either of the said pocket-strips 1 and 2, I first take a piece of fabric, as 3, of any suitable width and length, and provide the same with a series 45 of suitably-spaced holes or perforations 4. This strip is next folded upon itself, as at 5, so that the strip-portion 6 will rest upon the fabric 3, as shown in said Fig. 5, the main fabric 3 having its non-folded portion 7 extending beyond the longitudinally extending marginal edges 8 of the strip-portion 6, substantially as shown.

Then by means of a suitable sewing machine, or otherwise, the strip-portion 6 is 55 secured along the finished edge or fold 5 to the main portion of the fabric 3 by means of a straight line or row of stitching, as 9. At suitable intervals, corresponding to the locations of the previously-mentioned holes or 60 perforations 4, the said straight line or row of stitching 9 is interrupted, angular stitching, as at 10, being made in a direction toward the edge 8 of the strip-portion 6, and then back again toward the main line of 65 stitching, as at 11, the stitching continuing

in a straight line, as at 12, in line with the main stitching, thence once more angularly, as at 13, toward the edge 8 of the strip-portion 6, and back again, as at 14, toward the main line of stitching 9, parallel to the fold 70 5, in which direction the said main line of stitching continues, until the position corresponding to the location of the next-placed hole or perforation 4 is reached, where the same arrangement of angular and short- 75 stitching is made, and so on according to the number of snap-catch members with which the strips 1 and 2 are to be provided. The strip-portion 6 thus being secured to the main fabric 3, a series of receiving pockets 80 15 are provided by the stitchings 10, 11, 12, 13 and 14, between said portion 6 and the fabric. Into each pocket, thus produced, can be slipped a socketed post-receiving member, as 16 of a snap-catch, the said 85 member 16 being properly retained in place by the stitching which surrounds the same, with the socket-portion 17 of each member 16 being in direct registration with a hole or perforation 4. After the several pockets 90 15 have been supplied with the fastener members 16, the non-folded portion 7 of the main fabric 3 is folded over upon the strip-portion 6 and is secured in place by a second line or row of stitching, as 18, in close proximity to the line of stitching 9, substantially as indicated in Fig. 4 of the drawings.

Referring to the base-strip 2, the same is also made from a piece of fabric which is provided with holes or perforations, as 4, is 100 folded in manner represented in said Fig. 5 of the drawings, and stitched and secured by the sewing herein-above described, so as to provide the said base-strip 2 with a series of pockets 19, each pocket 19 having disposed therein, in the manner above described, a fastener-member 20 carrying the usual snap-post 21, and each post extending into and projecting from a hole or perforation 4. Thus, as will be clearly evident from 110 an inspection of Figs. 2 and 3, the respective members of snap-catches or fasteners are readily and positively secured with relation to the respective strips 1 and 2, so that the said strips can be readily secured in their 115 connected relation, and can be easily separated, when necessary.

If desired, the strips 1 and 2 may be folded and stitched in the manner represented in Figs. 6 and 7 of the drawings, 120 each strip comprising a main piece of fabric, as 22, provided with suitably disposed holes or perforations 23, as shown more particularly in Fig. 7 of the drawings, which serve the same purposes as the hereinbefore 125 mentioned holes or perforations 4. Each piece of fabric 22 is doubled over, as at 24 and 25, so as to provide a narrow strip-portion 26 and a wide strip-portion 27, which are arranged in such a manner, so as to have 130

the lapped-over relation represented more particularly in Fig. 7 of the drawings. The wide strip-portion 27 is next sewed fast to the main fabric 22, by means of the stitching 9, 10, 11, 12, 13 and 14, in the manner herein-before described, so as to provide receiving pockets, as 28, into which the respective fastener-members of the separable snap-catches are slipped and retained therein by a line of stitching or sewing, as 29, passed through the main fabric 22, the lower part of the strip-portion 27, and the intermediately disposed narrow strip-portion 26, in the manner illustrated in said Fig. 7 of the drawings.

In the construction and arrangement of parts represented in Figs. 8 and 9 of the drawings, is shown a base-strip, as 30, an upper strip-member 31, and an outer face-strip 32, the latter having its longitudinally extending marginal edge-portions lapped under and extending inwardly toward each other, as at 33 and 34, the part 33 resting upon the base-strip 30, and the part 34 resting upon the strip-member 31. The lower part of the face-strip 32 and its part 33 are then sewed fast to the base-strip 30 by means of the stitching 35, 36, 37, 38, 39 and 40, and the part 34 is similarly sewed fast to the strip-member 31 by means of the stitching 41, 42, 43, 44, 45, and 46, so as to provide receiving pockets, as 47, for the reception of the respective members of the snap-catches, as will be evident from an inspection of said Fig. 9. The base-strip 30 and the face-strip 32, with the intermediately disposed part 34 and the strip-member 31 are then securely united by means of a straight line or row of stitching 48 in close proximity to the stitching 41, 42, 43, 44, 45 and 46.

Fig. 10 represents an arrangement of strip-members or elements similar to the arrangement of strip-members described in connection with the construction illustrated and described in connection with Figs. 6 and 7, the various parts being united and the fastener-member pockets being formed by an arrangement of stitching, as 49, 50, 51, 52, 53, 54, 55 and 56, and 57, 58, 59, 60, 61, 62, 63 and 64, and the straight line of stitching 65.

In Fig. 11 I have illustrated an arrangement of the several members, in which I have dispensed with the form of stitching 57, 58, 59, 60, 61, 62 and 64, but in which I make use of the stitching 51, 52, 53, 54, 55, and 56, as well as the single straight line of stitching 65.

In the construction illustrated in Figs. 12, 13 and 14, the reference-character 66 indicates a perforated face-strip or member, having its longitudinally extending marginal portions folded under, as at 68, and suitably disposed upon the back of said strip 66, at intervals corresponding to the

locations of the holes or perforations 73, are narrow back-strips 67, placed transversely, as shown in Fig. 13, the said back-strips 67 also, preferably having their ends folded under, as at 69, said folded-under ends being 70 disposed beneath the folded-under edge-portions 68 of the face-strip 66. The various strips 66 and 67 are sewed together, so as to secure the same in their assembled relation and to provide the fastener-member receiving pockets 74, by means of the lines of longitudinally running stitching 70 and 71, and the transversely running stitching 72, as illustrated in said Figs. 12 and 13 of the drawings.

In Fig. 15, I have shown another modification, comprising a folded over strip or member 75—76, suitably perforated, as above, the folded-over portions being secured together by means of the stitching 77, 78, 79 and 80, said stitch-portions 78, 79 and 80 also providing suitable pockets, as 81, for the reception of the fastener-members of snap-catches. To prevent displacement of the fastener-members from their respective pockets 81, a row or line of stitching, as 82, is also provided.

From the foregoing description of the present invention it will be seen that I have provided by the several fastener-containing and retaining strips or bands, a simple, neat and well-appearing fly for garments, the separable fastener-members of the snap-catches being entirely covered and secured in the variously-produced receiving pockets, 100 in which the metallic fastener-members are prevented from rusting. Furthermore, the general construction is simplified because of the fact that the fasteners can be easily and quickly inserted in place in the pocket-like 105 receiving spaces formed between the cover-strip and the base-fabric, without the necessity of sewing each fastener independently in position, or by the employment of other means for securing the fasteners in place, 110 each fastener being retained in its operative position, against wobbling or tilting motion, and against displacement from between the said cover-strip and base-fabric.

Of course, I am aware, that some changes 115 may be made in the general arrangements and combinations of the stitchings with the cover-strip and base-fabric, without departing from the scope of the present invention, and as defined in the clauses of the claims 120 which are appended to the said specification. Hence, I do not limit myself to the devices and parts as described in the said specification, and as illustrated in the accompanying drawings.

I claim:

1. A fastener-strip or fly for garments in the form of a piece of fabric comprising a face-member and a rear-member, said face-member being provided with suitably dis- 130

posed holes or perforations, fastener-members disposed between said face and rear members, the locations of said fastener-members corresponding to the holes or perforations in said face-member, and stitching for securing said members together, said stitching comprising a longitudinally extending line of stitching and transversely extending stitching to provide closed pockets in which said fastener-members are disposed and concealed against removal and loss.

2. A fastener-strip or fly for garments in the form of a piece of fabric comprising a face-member and a rear-member, said face-member being provided with suitably disposed holes or perforations, fastener-members disposed between said face and rear members, the locations of said fastener-members corresponding to the holes or perforations in said face-member, and stitching for securing said members together, said stitching comprising a longitudinally extending line of stitching and transversely extending stitching to provide closed pockets in which said fastener-members are disposed and concealed against removal and loss, and an additional straight and uninterrupted line of stitching, portions of said latter stitching providing closures for said pockets.

3. A fastener-strip or fly for garments in 30 the form of a piece of fabric comprising a face-member and a rear-member, said face-member being provided with suitably disposed holes or perforations, fastener-members disposed between said face and rear- 35 members, the locations of said fastener-members corresponding to the holes or perforations in said face-member, a main line of stitching for securing said members together, tying stitches interrupting said main line 40 of stitching, said tying stitches extending angularly from said main line of stitching and lying in close proximity to said fastener-members and thereby providing closed means to prevent movement of the said fas- 45 tener-members between said stitches against removal and loss, and an additional straight and uninterrupted line of stitching providing a means for the displacement of said fastener-members from between said tying 50 stitches.

In testimony that I claim the invention set forth above I have hereunto set my hand this 29th day of June, 1917.

LEO ROSENMAN.
